UNITED STATES PATENT OFFICE.

THOMAS C. SCHUYLER, OF BROOKLYN, NEW YORK, ASSIGNOR TO LOGAN IRON WORKS, OF BROOKLYN, NEW YORK, A CORPORATION OF NEW YORK.

STEAM-COOKER.

1,086,093.

Specification of Letters Patent.

Patented Feb. 3, 1914.

Application filed May 1, 1913. Serial No. 764,896.

To all whom it may concern:

Be it known that I, THOMAS C. SCHUYLER, a citizen of the United States, residing at Brooklyn, in the county of Kings and State 5 of New York, have invented certain new and useful Improvements in Steam-Cookers, of which the following is a specification.

My invention relates to steam cookers, or apparatus used for the preparation and 10 treatment of large quantities of cotton seed, fish, or similar materials, to be subsequently operated upon in oil presses.

The objects of my invention are, first, to so construct and arrange the parts that the 15 steam or cooking medium can be so regulated, that the temperature and steam can be controlled and modified at any one of the different sections of the cooker independent of the other sections, and without 20 it being necessary to stop the apparatus or effect the feeding of the material into the apparatus, or its discharge therefrom. Second, to provide means whereby the operation can be made a continuous one and the material fed through the cooker uninterrupted 25 and of varying speeds if so desired. Third, to so arrange the parts of the cooker so that access may be readily had to any of the parts in order to quickly examine the same 30 and make necessary adjustments, or repairs, or replace broken parts in the least time and at a minimum cost.

Further objects and advantages will appear from the detailed description herein- 35 after referred to.

The invention consists of structural features and relative arrangements of the different parts comprising the invention which will be hereinafter more fully described and 40 particularly pointed out in the appended claims.

In the drawings in which similar reference characters indicate the same parts in the several figures of drawings: Figure 1 45 is a side view of the cooker, partly in longitudinal section to show the interior construction of the barrel; Fig. 2 is a plan view, partly in section to show the interior of the barrel; Fig. 3 is an enlarged sectional view 50 of the cooker at the outlet end of the barrel; Fig. 4 is a section on line 4—4 of Figs. 1 and 3; Fig. 5 is a section on line 5—5 of Figs. 1 and 3; and Fig. 6 is an enlarged fragmentary section of a coupling or diaphragm 55 of the inner steam spray pipe shaft.

In the drawings, 1, 1, are structural steel pedestals or base sections and braces, which rigidly support and firmly hold the imperforate, container barrel 2, having the inlet head 3, and outlet or discharge head 4; said barrel 2, being provided with the feed neck for the attachment of inlet chute 5 for feeding of the material, and manholes and covers 6, for access to the interior of the barrel to permit examination, adjustment and repair of all parts within the same.

7 is a discharge opening in the lower side of head 4, having a pivoted door plate 8 for varying the size of discharge opening 7.

Base pieces 9 are provided with cross 70 pieces 10 and braces 11, for rigidly supporting the journal boxes 12 carrying the shaft 13, of the driving gear, to be presently described. Fastened to said shaft 13 is a sprocket wheel 14 for slow speed, and 75 sprocket wheel 15 for high speed, and a drive pinion 16 engaging the drive gear 17, attached to and for rotating the steam spray pipe shaft sections within the barrel, and to be hereinafter described.

The numeral 18 designates a countershafting carrying high and low speed sprocket wheels 19 and 20, engaged by a sliding clutch 21, controlled by a lever 22, said wheels 19 and 20 being geared to wheels 14 85 and 15, by means of well known sprocket chains 23 and 24, as shown.

25 represents a perforated, rotatable steam spray pipe shaft within the barrel 2, preferably at the outlet end and which 90 passes at one of its ends through a suitable opening and packing in the discharge head 4, while its other or inner end rests in diaphragm 28 which is rotatably supported in a bearing 26, fixed to the inside of the barrel, as shown in Figs. 2 and 5.

27 is a section of a perforated steam spray pipe shaft forming a continuation of the section 25, and separated therefrom by a diaphragm 28, and 29 is a similar section 100 extending from the end of section 27 and separated therefrom by the diaphragm 30. Said section 29 passes through an opening, provided with steam tight packing, in the inlet head 3, and is provided on its outer 105 end with a solid removable cap 31. Each of said sections 25, 27 and 29, are provided with suitable perforations 32 for the purpose of permitting steam or other heating or cooking medium to pass from the interior 110

of said sections into the interior of the barrel 2, and each of said diaphragm sections 28, and 30, rest in bearings 26, thereby rotatably supporting the full length of sections of spray pipe shafts 25, 27 and 29, properly and equidistant from the inner wall of the barrel.

32', 32", are combined mixers and conveyer paddles arranged radially and secured 10 to the different sections of the rotary spray pipe shafts 25, 27 and 29, and rotate with the same, for the purpose of not only thoroughly mixing and agitating the material fed into the barrel 2, by the feed chute 5, but 15 also convey the said material through the barrel from right to left, and finally out through the discharge opening 7, to be received in any suitable conveyer, through 33.

34 is a stationary steam distribution cylinder, rigidly held and supported by means 20 of a standard 35 secured to the base pieces 9, and is closed at its outer end by a removable cap 34', and open at its inner end to snugly receive the outer and imperforate end of the 25 rotatable spray pipe section 25, which passes through a suitable opening and packing in the discharge head 4, as shown in Fig. 3. Surrounding and secured to the outer end of section 25 and interposed between the drive 30 gear 17, and head 4, and abutting against said head, is a thrust collar 36.

37 is a central imperforate rotary steam pipe, leading from the interior of section 29, through the diaphragms 30 and 28, sections 35 27 and 25, and head 4, to the interior of the forward end of the steam distribution cylinder 34, and passing through and connected to a piston 38, revolving in said cylinder 34. Connected at one of its ends to the diaphragm 28, and situated within the spray 40 pipe shaft 25 and surrounding the pipe 37 and separated therefrom is a second rotary steam feed pipe 39, which also passes through the head 4 and into the cylinder 34, and is also connected to a rotary piston 40, in the same manner as pipe 37, and as shown 45 in Fig. 3.

The rotatable, perforated spraying pipe shaft 25 is extended through the head 4 and 50 thrust collar 36, by an imperforate section, whose outer end surrounds the pipe 39 and also is separated therefrom, and is rotatably supported in the open end of the cylinder 34 which is provided with a gland 41 to insure a tight joint between the said shaft 25 and cylinder 34.

42 is a main steam supply pipe which in 55 the present invention is provided with three branches 43, 43' and 43", each having its own controlling valve 44, 44' and 44", respectively, and lead into the cylinder 34 on different sides of the pistons 38 and 40, as shown, so that pipe 43 communicates with the interior of pipe 37, pipe 43' with 39, and 60 pipe 43" with spray pipe shaft 25.

45, 45' and 45" are drip pipes connected with the bottom of the cylinder 34 on different sides of the pistons 38 and 40 and are controlled by suitable valves, and lead to a common drain pipe 46, for the purpose of 70 withdrawing any water accumulated in the cylinder 34, due to condensation of the steam.

47 represents a lagging which may be placed on the outside of the barrel 2 for the purpose of insulation, and for retaining the 75 heat within the barrel.

If it is desired, the pitch of the paddles 32' may vary from the inlet end toward the outlet, and preferably are so arranged that the paddles attached to section 29 will cause 80 the material to travel faster than the paddles of section 27, and paddles of section 25 advance the material slower than the paddles attached to section 27.

While I have shown and described three 85 spraying or heating sections, 25, 27 and 29, I do not care to limit myself to this exact number, as this number could be varied more or less, without departing from the essential features of my invention. Furthermore, 90 while I have shown the conveyer paddles attached to the rotary spray pipe sections, this is not essential for carrying out the invention, as the conveyer flights may be attached to the barrel which can be rotated, 95 and the pipe section so as to be stationary, as will be readily understood by one skilled in the art, but I have herein illustrated my preferred form.

The operation of the apparatus is as follows:—The uncooked material is fed at a uniform rate into the chute 5, and the clutch 21 is thrown so as to engage either of the sprocket wheels 19 and 20, depending on what speed it is desired to rotate, by means 100 of intermediate shaft 12 and gears 16 and 17, the inner spray pipe sections 25, 27 and 29, with their attached conveyer paddles 32'. The live steam is admitted into the different sections 25, 27 and 29 by opening 105 the valves 43, 43' and 43", and the amount of steam issuing through the openings 32 of each of said sections into the barrel 2, is separably and independently controlled, depending upon what valve is operated. The material within the barrel is agitated by said paddles 32' and conveyed through different zones of heat and steam density, moving 110 along the section 29 at a certain speed, then slower at section 27, and slowest at 25. The 115 maximum of cooking is effected at section 29, owing to great capacity or volume of steam in said section 29 as compared with that of section 25, and by opening the valve 43 a greater quantity of steam can be admitted in 120 said section 29. The spray section 25, by proper adjustment of valve 43" can control the steam to such an extent as to cause a portion of pipe section 25 to act as a hot baking pipe before the material is finally 125 130

discharged out of the opening 7 into the conveyer 33. In order to control the steam pressure and spraying in the section 27, one adjusts the valve 43'. From this method of operation it will be seen that by means of said valves 43, 43' and 43'', the quantity or pressure of steam in sections 25, 27 and 29, can be simultaneously or independently controlled of each other, and without interfering with the operation of the machine, and so regulate and absolutely control the various heating or cooking zones within the barrel 2, to satisfactorily and efficiently treat all conditions, and varying characteristics of constantly changing material. The drip pipes 45, 45' and 45'' not only can be used for draining the water of condensation from the cylinder 34, but to release the excess of steam or pressure in any one of the sections 25, 27 or 29, after the proper valve 43, 43' or 43'' is closed. Should it be found that the material is progressing through the cooker too rapidly, the clutch 21 can be thrown from engagement with the sprocket wheel 20, to the wheel 19, and if a higher speed is desired, the clutch 21 is moved from the wheel 19 to engage 20, thus a further condition of regulation of the material is had in addition to the control of temperatures and steam supply, as above explained.

From the foregoing disclosure of construction and mode of operation of the invention, it will be seen that the apparatus is capable of cooking material of variable quality continuously and progressively, with an economical use of the steam, and at the same time produce a better and uniform product in one apparatus in continuous operation; and all regulations of the operations being accomplished without interruptions to the apparatus. Also by having the steam distributing pipe 37 within the sections 25, and 27, and pipe 39 within section 25 and the pipe 37, and said pipes 37 and 39 leading to a common distribution cylinder 34, this enables the valves 44, 44' and 44'', respectively controlling the steam of the sections 29, 27 and 25, to be placed in such proximity to each other at the discharge end of the cooker, as to be quickly and readily controlled at one point of the cooker by a single person, without being required to move from his position at the discharge end, while observing the material passing out of the opening 7, and in this respect differs and has great advantages over prior cookers, in which the pipe sections and steam connections are so arranged that a person is required to travel from one place to another, up and down the full length of the cooker, in order to control the different sections.

What I claim is:—

1. A cooker comprising a horizontal imperforate barrel having an inlet and an out-

let, a steam distributing or spraying pipe extending longitudinally within said barrel and divided into a plurality of separate and independent compartments or sections, a steam distribution casing exterior of said barrel and having an independent connection with each of the spray pipe sections for conveying the steam to any one of the said compartments or sections, and a separate means for each connection and section for controlling the supply of steam to any one of the sections independent of the other sections. 70

2. A cooker comprising a horizontal imperforate barrel having an inlet and an outlet, a steam distributing or spraying pipe rotatably mounted and extending longitudinally within said barrel and divided into a plurality of separate and independent compartments or sections, a stationary steam distribution casing exterior of said barrel and having an independent connection with each of the spray pipe sections for conveying the steam to any one of the said compartments or sections, and a separate means for each connection and section for controlling the supply of steam to any one of the sections independent of the other sections. 80

3. A cooker comprising a horizontal imperforate barrel having an inlet and outlet, a steam distributing or spraying pipe consisting of a plurality of separated and independent concentric sections and extending longitudinally within said barrel, and means for controlling and varying the distribution of the steam along the length and sections of said spraying pipe. 95

4. A cooker comprising a horizontal imperforate barrel having an inlet and outlet, a steam distribution casing, a steam distributing or spraying pipe consisting of a plurality of separated and concentric sections having independent connections with said distribution casing extending longitudinally within said barrel, means for conveying material through the barrel from the inlet to the outlet, and means for controlling and varying the distribution of the steam along the length and sections of said spraying pipe. 105

5. A cooker comprising a horizontal imperforate barrel having an inlet and outlet, a steam distribution casing, a rotary steam distributing or spraying pipe consisting of a plurality of separated and concentric sections having independent connections with said distribution casing and extending longitudinally within said barrel, conveyor paddles attached to said rotary pipe for advancing material from the inlet to the outlet, and means for controlling and varying the distribution of steam in the different sections of the spraying pipe. 110

6. A cooker comprising a horizontal imperforated barrel having an inlet and outlet, 130

a steam distribution casing, a rotary perforated steam distributing or spraying pipe consisting of a plurality of separated sections having independent connections with 5 said distribution casing and extending longitudinally within said barrel, means for varying the rotation of said spraying pipe, conveyer paddles attached to said rotary pipe for advancing material through the 10 barrel from the inlet to the outlet, and means for controlling and varying the outlet of steam in different sections of the spraying pipe.

7. A cooker comprising a horizontal imperforate barrel having an inlet and outlet, 15 a steam distribution casing, a perforated steam distributing or spraying pipe consisting of a plurality of separated sections having independent connections with said 20 distribution casing and extending longitudinally within said barrel, means for conveying material through the barrel from the inlet to the outlet, and means for controlling and varying the supply of steam into 25 the connections, and the outlet of the steam from the different sections along the length of said spraying pipe.

8. A cooker comprising a horizontal imperforate barrel having an inlet and outlet, 30 a steam distribution casing, a steam distributing or spraying pipe consisting of a plurality of separate sections having independent connections with said distribution casing and within said barrel, and means 35 operating with each of said connections for controlling and varying the outlet of the steam from each of said sections independent of the other sections.

9. A cooker comprising a horizontal stationary imperforate barrel having an inlet 40 and outlet, a steam distribution casing, a rotary perforated steam distributing or spraying pipe within said barrel and divided into a plurality of separate and independent 45 concentric sections along its length and having independent connections with the distribution casing, and separate means coöperating with each of said connections for independently controlling and varying the outlet of 50 the steam from each of said sections independent of the other sections.

10. A cooker comprising a horizontal stationary imperforate barrel having an inlet and outlet, a steam distribution casing, a rotary perforated steam distributing or spraying pipe extending longitudinally within 55 said barrel having a plurality of independent sections separated from each other by a diaphragm and having independent connections with the distribution casing, means for conveying material through the barrel from the inlet to the outlet, a separate pipe having a valve connected with said distributing 60 casing and for each of said sections, for in-

dependently controlling and varying the outlet of steam from each of said sections.

11. A cooker comprising a stationary horizontal imperforate barrel having an inlet and outlet, a steam distribution casing, a rotary perforated heat distributing and 70 steam spraying pipe within said barrel having a baking or dry heating section at the outlet end and steam cooking sections toward the inlet, said heating and cooking sections having independent connections 75 with said distribution casing, conveyer paddles attached to said rotary pipe for advancing the material from the inlet to the outlet, and means for independently controlling and varying the outlet of heat from 80 the baking or heating section and the steam from the cooking sections of the pipe.

12. A cooker comprising a horizontal imperforate barrel having an inlet and outlet, 85 a steam distribution cylinder, a rotary perforated heat distributing and steam spraying pipe within said barrel divided into a plurality of sections, each of said sections having an independent connection with said steam distribution cylinder, and means for 90 independently controlling the flow of steam into said plurality of sections of said spraying pipe.

13. A cooker comprising a horizontal imperforate barrel having an inlet and outlet, 95 a steam distribution cylinder, a rotary perforated heat distributing and steam spraying pipe within said barrel divided into a plurality of sections, each of said sections having an independent connection with said 100 steam distribution cylinder, and means for independently controlling the flow of steam into said independent connections of said spray pipe sections.

14. A cooker comprising a horizontal imperforate barrel having an inlet and outlet, 105 a steam distribution cylinder, a rotary perforated heat distributing and steam spraying pipe within said barrel divided into a plurality of sections, each of said sections 110 having an independent pipe connection with said steam distribution cylinder and within each other, and means for independently controlling the flow of steam into said independent pipe connections of said spray pipe 115 sections.

15. A cooker comprising a horizontal imperforate barrel having an inlet and outlet, 120 a steam distribution cylinder, a rotary perforated heat distributing and steam spraying pipe within said barrel divided into three sections, each of said sections having an independent connection with said steam distribution cylinder, and means for independently controlling the flow of steam into 125 said distribution cylinder and independent connections of said spraying pipe sections.

16. A cooker comprising a horizontal im-

perforate barrel having an inlet and outlet, a steam distribution cylinder divided into three compartments, an independent steam pipe and controlling valve for each of said compartments, a rotary perforated heat and steam spraying pipe within said barrel divided into three independent sections, a pipe for each of said spray pipe sections connecting the interior of its section with the interior of one and a different compartment of the steam distribution cylinder from that of the other sections.

17. A cooker comprising a horizontal imperforate barrel having an inlet and outlet, a steam distribution cylinder divided into three compartments, an independent steam pipe and controlling valve for each of said compartments, a rotary perforated heat and steam spraying pipe within said barrel divided into three independent sections, a pipe for each of said spray pipe sections connecting the interior of its section with the interior of one and a different compartment of the steam distribution cylinder from that of the other sections, said pipes connecting the com-

partments with the spray pipe sections being concentric with each other.

18. A cooker comprising a horizontal imperforate barrel having an inlet and outlet, a steam distribution cylinder divided into three compartments at the outlet end of said barrel, an independent steam pipe and controlling valve for each of said compartments, a rotary perforated heat and steam spraying pipe within said barrel divided into three independent sections, a pipe for each of said spray pipe sections connecting the interior of its section with the interior of one and a different compartment of the steam distribution cylinder from that of the other sections, said pipes connecting the compartments with the spray pipe sections being concentric with each other.

In testimony whereof I affix my signature in presence of two witnesses.
